UNITED STATES PATENT OFFICE.

JOHN A. BRADSHAW, OF LOWELL, MASSACHUSETTS, ASSIGNOR, BY DIRECT AND MESNE ASSIGNMENTS, OF THREE-FOURTHS TO JAMES LEACH, ORANGE V. SMITH, AND THOMAS F. BYRON, ALL OF SAME PLACE.

MUSIC-BOX.

SPECIFICATION forming part of Letters Patent No. 310,645, dated January 13, 1885.

Application filed March 30, 1883. (No model.)

To all whom it may concern:

Be it known that I, JOHN A. BRADSHAW, of Lowell, in the county of Middlesex and State of Massachusetts, have invented certain Improvements in Music-Boxes, of which the following is a specification.

My invention relates to music-boxes; and it consists in certain improvements in construction, whereby the cylinders may be changed while the box is in operation.

In the accompanying drawings, which illustrate my invention, and form part of this specification, Figure 1 represents a plan of my improved instrument. Figs. 2 and 3 are end elevations of opposite sides of the same. Fig. 4 is a sectional elevation on the plane of line $x x$, Fig. 1. Fig. 5 is a sectional elevation on the plane of line $y y$, Fig. 1; and Fig. 6 is a detail view of the fan-regulator on the right-hand side of the instrument.

Like letters designate corresponding parts in all of the figures.

A, Fig. 1, is a comb or set of steel springs which produce the musical sounds.

A' is a metallic plate to which the comb is attached.

F F are cylinders with pins set in their surfaces, which play the tunes. These cylinders are mounted on shafts D D, which have their bearings in circular plates C' C', one at each end of the cylinders. Said plates C' C' are secured to a central shaft, B, which is supported by bearings B' B' at each end. The cylinders F F and their shafts D D are rotated by a main-spring and drum, R. The mainspring and drum are mounted upon an arbor supported in standards $h h$, and provided with the usual ratchet, D', pawl E, and spring I', to prevent the uncoiling of the mainspring.

S S' S'' are intermediate gears which connect the mainspring-drum with the shafts D and their cylinders F F.

D' is a gear on the end of each cylinder-shaft, which connects with the gear-wheel S'', and thus gives rotary motion to the cylinder.

G is a gear-wheel on the opposite end of each of the cylinder-shafts, which gives motion to the shaft J through the pinion I on the end of said shaft.

Mounted on the shaft J is a gear-wheel, K, which conveys motion to the screw M and fan

M' through an intermediate gear and pinion, L. The screw M has its bearings at the top at o in the stand o , and at the lower end at o' , Fig. 6. Said fan acts as a regulator to the rotary motion of the cylinders, thus causing the tunes to be played in proper time. Each cylinder F is connected with the gear G by a pin, h, fastened permanently in the gear, said pin passing through a hole in the cylinder-head, thus 60 rotating the cylinder with the shaft and gear. There is a cam and ratchet-wheel, a, attached to the inner-side of each gear-wheel G, between said gear-wheel and its cylinder. At every rotation of the cylinder this ratchet-gear a comes 65 in contact with a projection, i', Fig. 5, on the side of the lever b, thus turning the ratchet and cam one notch. The cam bearing on the end of the pin a' in the head of the cylinder F, Fig. 1, moves the cylinder on the shaft, presenting 70 another series of pins to the ends of the steel springs A, thus changing the tune with every rotation of the cylinder. When there has been an entire rotation of the ratchet-gear and cam, the cylinder is moved back to its first position 75 by a spiral spring, E, placed around the cylinder-shaft, between the head of the cylinder and its bearing at the end opposite from the ratchet-gear, thus bringing the cylinder in position to repeat the first tune. There are four cylinders placed in bearings equidistant from the center shaft, B, said cylinders having bearings $m m$, with stands C C. Said stands and bearings are permanently fastened to the circular plates C' C' by screws $n n$, as shown in Fig. 4. 85

H H are set-screws passing through flanges O O, formed on the stands C C. These set-screws bear upon the outer edge of the circular plates C', and regulate the distance of the cylinders from the points of the springs A, thus giving 90 the desired amount of vibration. Each cylinder is held in its place by the slide P, Fig. 4, which has a groove in the end V, which engages a projection, H', on the stand C. This slide is held in place by the lever P' and connecting-link V', and it rests upon the top of the stand Q, the lever P' being attached to the slide P by a pin, z, and its lower end to the stand Q by a screw, z', the stand Q being permanently attached to the plate A'. When it is desirable 95 to play a new series of tunes, the slide P is withdrawn by means of the lever P', thus re-

leasing the cylinder, which is replaced by another, which is secured in proper place by the slide P being returned to its former position.

W is a lever that is fastened to the stand Q 5 by a screw, W', at the lower end of the lever, said lever being placed at right angles to the slide P at the end opposite the end V. This lever W is moved to the right when it is desired to change cylinders, thus releasing the 10 slide P, which is then withdrawn and the cylinders changed. The slide is then replaced and the lever W is moved to the left, thus securing the slide in its place. The lever W, as shown in Fig. 1, is connected with the lever U 15 by a connecting-rod, Y.

U' is a pin near the middle of the lever U, on which the lever turns when the lever W is moved. The opposite end of the lever U enters a groove in the coupling T', and said coupling is thus moved on the shaft X. The coupling is connected with the shaft by a pin in the shaft and a groove in the hub of the coupling, between the shaft and the coupling, the shaft thus giving motion to the coupling. When 25 the lever W is moved to the right, the coupling T' is brought into contact with the gear-wheel T, (said gear-wheel being loose on the shaft X,) thus giving rotary motion to the gear-wheel T by means of teeth cut in the end of the coupling, which mesh with teeth cut in the end of 30 the hub of the gear-wheel. This gear-wheel imparts motion to the pinion and gear L', said gear connecting with a rotary screw, M², and fan M³, (said screw having a bearing at the top 35 end at O⁴ in stand O⁵, and at its lower end in the same stand at O⁶,) thus acting as a regulator to prevent a too rapid motion of the main-spring-drum and train of gears when the cylinders are being changed, and the first regulator stops by being disconnected from the gear G on the end of the cylinder-shaft. This disconnection is being made while the cylinders are being changed, and when the gear G is moved away from the pinion I, and before the 40 gear G of the next cylinder takes its place.

When the cylinders are changed for a new series of tunes, and the cylinder is in its proper place and held there by the slide P and projection H', the first regulator is put in motion, the lever W being moved to the left, thus securing the slide P in its place and releasing the second regulator from action. 50

In Fig. 5 are represented sounding-boards t t, made of pine or spruce. These boards are connected together by narrow strips of the same wood, v v. The object of these sounding-boards is to increase the volume of sound. d d are projections on the under side of the plate A'. The sounding-boards are secured to the under side of said plate by bolts CC, CC—one at each 60 end of the plate.

I am aware that a music-box with a series of cylinders upon a common rotating shaft, whereby the cylinders may be brought in succession into engagement with the comb, is not 65 new, as it is shown in the Patent, No. 105,972, to A. Paillard; but, so far as I am aware, such an arrangement has been confined to music-boxes operated by hand, and has never been used prior to my invention in automatic or 70 self-playing music-boxes.

I claim as my invention—

1. In a music-box, the disks C' upon the shaft B, a series of cylinders mounted thereon, with the bearings C, flanges O, and set-screws H, in 75 combination with the slide P and levers P' and W, as set forth.

2. In a music-box, the disks C' upon the shaft B, having mounted thereon a series of cylinders, with bearings or stands C, having flanges O, set-screws H, and projections H', in combination with the slide P, levers P' and W, connecting-rod Y, lever U, coupling T', gear-wheel T, gear and pinion L', screw M², and fan M³, substantially as set forth. 80

JOHN A. BRADSHAW.
